UNITED STATES PATENT OFFICE.

WILLIAM A. NORMAN, OF CHICAGO, ILLINOIS.

ROLL-PAPER SHOE.

1,242,966.

Specification of Letters Patent. Patented Oct. 16, 1917.

Application filed October 4, 1915. Serial No. 54,107.

To all whom it may concern:

Be it known that I, WILLIAM A. NORMAN, a citizen of the United States, residing at Chicago, in the county of Cook and State 5 of Illinois, have invented a certain new and useful Improvement in Roll-Paper Shoes, of which the following is a specification.

My invention relates to shoes for the handling of roll-paper. It will be understood by those familiar with the print paper trade that there is annually a tremendous loss in connection with paper rolls due to the crushing of the edge of the paper when the roll is tilted during handling. Much of 10 the roll print paper, especially that intended for newspaper work, is comparatively thin and tender and the edge of the paper crushes when the roll is tilted up on edge in putting it in or out of the freight 15 cars and in preparing to place the roll in the press. The object of my invention is to provide simple and efficient means for protecting the paper and distributing the weight over a considerable portion of the 20 roll thereby rendering it possible to tilt the roll as frequently as desired without doing any damage to the paper.

I accomplish my object by the device shown in the accompanying drawings, in 25 which—

Figure 1 is a perspective view thereof.

Fig. 2 is a transverse section thereof on the line 2—2, Fig. 1.

Fig. 3 is a side elevation of a roll showing my shoe applied thereto.

Similar numerals refer to similar parts throughout the several views.

The shoe consists preferably of sheet steel and may be one-sixteenth of an inch thick 40 more or less. In the form shown, it consists of two pieces, a sole 1 and a back 2. When viewed in plan the outer edge of the sole conforms to the arc of a circle and the inner edge 1^a is sharpened to a dull edge 45 to facilitate its insertion under the rolls of paper. This inner edge is parallel to the chord of the arc formed by the periphery but lies closer to the center of curvature and therefore is wider than a mere segment of the arc would be. This affords 50 more area and also facilitates insertion under the roll. In other words, the sole curves toward the center at the ends 1^b and hence the width of the shoe from the inner edge 55 1^a to the arc 1^c is greater than it would otherwise be.

The outer edge of the sole is turned up to form a flange 1^d which is riveted or otherwise securely fastened to the lower edge of the back 2 and backs up the portion 2, as 60 shown in the drawings. This results in two advantages; first, all strain on the rivets is removed, for the weight of the rolls when tilting tends to keep the back and the flange in contact; second, an extra quantity of material is afforded at the corner where the greatest stress occurs and hence the life of the device is greatly prolonged. There is another advantage arising from the fact that the flange is integral with the sole as 65 70 there is no danger that the parts will become separated in use.

The back when viewed in elevation is approximately triangular, the center point 2^a being highest and being preferably approximately six inches high. The ends 2^b do not descend to the level of the sole but have vertical ends which are approximately two inches high. The back is curved outward 75 at the points 2^a and 2^b, the purpose being 80 to prevent at all hazards these points from cutting into the side of the roll. I have found that by rounding these slightly backward, the paper will be supported without 85 damage of any kind.

Operation: My shoe is intended for use only at those critical moments when the roll is being tilted up either during shipment or at the time when the roll is to be set in the printing press. It is intended simply to distribute the strain due to the weight of the roll over a large surface and hence enable the delicate paper to withstand the stress to which the roll as a whole is subjected upon the occasions mentioned. Let it be assumed 90 that a roll is standing upright in a freight car. In order to put it upon a truck it must be laid partially or entirely upon its side. In employing my shoe, when the roll is to be tilted, the operator first lays the shoe on the 95 floor near the roll. He then exerts a slight pressure sidewise against the roll near the top thus causing it to release part or all of its weight at that point from the floor but without actually tilting the roll. This lifts 100 the weight sufficiently to enable the operator to apply the shoe and slip it under in position by the aid of his foot. The forward or inner edge of the shoe being sharpened, 105 readily finds its way under the roll. When 110 the shoe has been inserted as far as it will go and the back 2 is in contact with the side

of the roll, the roll may be tilted, whereupon the shoe will tilt with it and the weight of the roll will be distributed over the entire surface of the shoe or at least a large part 5 of it depending upon whether the periphery of the roll is of the same curvature as the periphery of the shoe. A notable feature of my invention is that the shoe will operate upon rolls of different sizes and having a 10 curvature either greater or less than the curvature of the periphery of the shoe. In any case the end of the roll will bear upon the entire surface of the sole of the shoe and will bear upon a considerable 15 area of the back, for my shoe is so constructed that the curvature of its periphery conforms to the curvature of the commonest sizes of roll. When the roll has been tilted far enough for its weight to be carried by 20 the truck or the paper holder of the press, the shoe is no longer needed and falls away. From the foregoing it will be evident that 25 this article is extremely simple and yet prevents the crushing of the paper which is the occasion of such an important percentage of

loss in practically every shipment of paper that is made. The article is of great durability and in fact is indestructible in the ordinary sense of the term. Furthermore, it accommodates itself to rolls of different 30 diameters and requires no attaching means nor fastening devices during its use.

Having thus described my invention, what I claim as new and desire to secure by Letters Patent, is:

A shoe whereby rolls of print paper may be supported on edge without damage, said shoe having a flat sheet metal sole for contacting the end of the roll, the outer periphery of the sole being circular and having an upstanding integral flange, and a sheet metal back rising from said sole and being fastened to the inside of said flange whereby the device is reinforced at the corner, said back being cylindrical except 45 at the top where it is curved outwardly to prevent digging into the sides of the roll.

In witness whereof, I have hereunto subscribed my name.

WILLIAM A. NORMAN.
